CLAIM

The ornamental design for digital camera display screen with graphical user interface, as shown and described.

DESCRIPTION

FIG. 1 is a perspective view of a digital camera, showing the new design;

FIG. 2 is a front view thereof;

FIG. 3 is a rear view thereof;

FIG. 4 is a top view thereof; and

FIG. 5 is a left view thereof; and,

FIG. 6 is an enlarged view thereof, showing the display screen separately for clarity of illustration.

The broken lines showing the digital camera illustrate the environment of the claimed design and forms no part thereof. The broken lines within display screen in the drawings illustrate portions of the graphical user interface which form no part of the claimed design.
